Inventor:

Edward R. Graf

Edward R. Graf

Attorney:

UNITED STATES PATENT OFFICE.

EDWARD R. GRAF, OF WATERTOWN, WISCONSIN.

GARTER.

Application filed December 8, 1920. Serial No. 429,082.

To all whom it may concern:

Be it known that I, EDWARD R. GRAF, a citizen of the United States, and resident of Watertown, in the county of Jefferson and State of Wisconsin, have invented certain new and useful Improvements in Garters; and I do hereby declare that the following is a full, clear, and exact description thereof.

10 My invention relates to improvements in hose supporters, and particularly to that type which encircles the limb of the wearer.

My invention has as its object the provision of a hose supporter, which is neat and effective, and which can be easily and quickly adjusted to the correct size at the will of the wearer.

It is also an object of my invention to provide a supporter of the class described 20 in which the use of a clasp for securing the garter around the limb is dispensed with.

A further object of my invention is to provide a supporter in which the webbing, preferably elastic, may be renewed with the least possible effort, and it is preferred that 25 the webbing be so arranged that the stitching thereof in any manner may be dispensed with if desired.

In the accompanying drawings forming a 30 part of this specification,

Figure 1 is a view in perspective of the supporter in its preferred form.

Figure 2 is a top plan view thereof, and

Figure 3 is a view similar to Figure 2, 35 showing a modified form of the arrangement of the webbing.

The same letters of reference indicate corresponding parts in all the figures.

Referring to the drawings in detail, the 40 numeral 1 designates a strip of webbing, preferably elastic, of sufficient length to encircle the leg of the wearer and provided at each end with loops 2 and 3.

As shown in Figure 1, the loops are formed 45 by means of the slip buckles 4 and 5, which allow the webbing to be woven through, form the loops, and then by friction holds the free end between the webbing and the buckle, as will be apparent.

50 The loops of the webbing are adapted to

receive thereon the hose-engaging member 6, the same being formed of a single piece of wire, sheet metal, or the like, one end of which has formed thereon the V-shaped slot 7 in which the hose is gripped, that is 55 to say, by forcing or pinching a portion of the upper end thereof into the crotch of said slot.

The upper end of the member 6 has formed therewith a ring 8, having a loop 60 receiving entrance 9 through which the loops of the webbing are passed in order that they may be slipped upon the ring 8.

In securing the supporter around the limb, the loops 2 and 3 of the webbing are 65 adjusted by the wearer to the proper size, the member 6 then has the ring 8 slipped through one of the loops, the webbing passing around the limb, and the other loop then slipped upon the ring. The member 6 is 70 then free to engage the hose.

By this structure, it is apparent that I have provided a simple and efficient supporter, and furthermore, by the structure the webbing may be renewed as it wears out 75 with the least possible effort.

By reason of the fact that the opening of the ring, through which the loops are passed, is formed at the lower portion of the ring and adjacent the V-shaped slot 7, it will be 80 impossible for the member 6 to turn and thus prevents the loops accidentally slipping from the ring.

In Figure 3, I have shown a modified form of the webbing, one in which one of 85 the loops is formed upon the end of the webbing by stitching, as indicated at 3', the adjustable feature being given by the other loop, which is formed as in the preferred form.

From the foregoing, it is thought that the construction, operation and many advantages of the herein described invention will be apparent to those skilled in the art, without further description, and it will be 95 understood that various changes in the size, shape, proportion and minor details of construction may be resorted to without departing from the spirit or sacrificing any of the advantages of the invention.

Having thus fully described my invention what I claim as new, and desire to secure by Letters Patent, is:—

A supporter of the class described, comprising a single strand of wire, one end of which is bent to form a V-shaped hose-receiving slot, and the other end forming a ring having a loop receiving entrance, a webbing for encircling the limb and having

at each end a loop adapted to slip upon the 10 open ring when in use and said loops being freely movable upon said open ring.

In testimony that I claim the foregoing I have hereunto set my hand at Watertown, in the county of Jefferson and State of 15 Wisconsin.

EDWARD R. GRAF.
